UNITED STATES PATENT OFFICE.

THOMAS A. HAMILTON, OF EMMETSBURG, IOWA.

COLTER CLEANER.

Application filed May 17, 1923. Serial No. 639,616.

To all whom it may concern:

Be it known that I, THOMAS A. HAMILTON, a citizen of the United States, residing at Emmetsburg, in the county of Palo Alto 5 and State of Iowa, have invented certain new and useful Improvements in Colter Cleaners, of which the following is a specification.

This invention relates to colter cleaners, and more particularly to a scraper for removing dirt and the like from a colter wheel.

An object of the invention is to provide means for removing dirt from colter wheels 15 to prevent a wheel from clogging and to enable the user to obtain a clean cut.

By removing the dirt from the wheel, it is prevented from falling on the axle, thus preventing unnecessary wear on the bearings and prolonging the life of such parts.

A further object of the invention is the provision of a scraper that may be readily moved to an inoperative position.

In the accompanying drawings, I have shown one embodiment of the invention. In this showing:

Figure 1 is a side elevation of a colter wheel showing the invention applied,

Figure 2 is a plan view,

Figure 3 is a detail sectional view on line 3—3 of Figure 1,

Figure 4 is a detail view of the scraper blade, and,

Figure 5 is a detail view of a supporting bracket.

Referring to the drawings, the reference numeral 1 designates the forked ends of a colter arm adapted to carry a colter wheel. The wheel comprises a disk 2 having a hub 3. This hub is provided with a central opening for the reception of an axle carried by the colter arms.

As shown in Figure 2 of the drawings, a scraper blade is arranged on each side of the wheel. As the construction of each of these devices is the same, a detail description of one will suffice. A bracket 4 is mounted on each end of the axle and extends upwardly. This bracket is provided with a suitable opening for the reception of a rod 5. A sleeve 6 surrounds this rod and is rotatable thereon. The rotation of the sleeve is limited by a set screw 7, mounted in the rod and received in a slot 8, in the sleeve. The sleeve is provided with an extension 9 having an opening 10. A scraper blade 11 is

connected to this sleeve. As shown, the upper edge of the blade is provided with a flange 12 having an opening 13. The blade is connected to the sleeve by means of a bolt 60 passing through the openings 10 and 13. A pair of cotter pins 14 are arranged in openings in the rod 5 adjacent each end of the scraper blade. These pins pass through the loops 15 formed on the ends of coil springs 16, the springs being arranged around the rod. As shown, the springs are provided with U-shaped offset central portions 17, adapted to bear against the scraper blade and force it toward the colter wheel. The 70 inner end of the rod 5 is supported in a bracket 18. As shown, this bracket is provided with a base 19, having openings 20 for the reception of the ends of a U-shaped bolt 21. The bolt 21 surrounds the colter arm, as shown in Figure 3 of the drawings, and nuts 22 are arranged on the ends of the bolt. The bracket is secured to the base by means of a pin 23 (see Figure 3) which permits the bracket to rotate about said pin 80 as an axis. The bracket is provided with a pair of parallel arms 24, having openings 25. A sleeve 26 is pivotally mounted in these openings by means of pins 27, and the sleeve is adapted to revolve about these pins 85 as an axis. The rod 5 passes through the sleeve 26 and is thus connected to the colter arm by the universal joint. The inner end of the sleeve is provided with grooves 28 adapted to receive a pin 29 carried by the 90 rod 5 to retain the rod in an adjusted position when the pin is in the grooves. The pin is retained in the grooves by means of a spring 30 surrounding the rod 5 and arranged between the sleeve 26 and a washer 31. A cotter pin 32 passes through an opening in the rod 5 to retain the washer 31 in position.

In operation, the portion 17 of the spring 16 forces the scraper blade 11 toward the colter wheel 2 to remove any dirt or other foreign matter from the surface of the wheel. The rod 5 is held in an adjusted position by means of the pin 29 received in the grooves 28. Any irregularities in the colter wheel due to wear are compensated for by the swivel mounting of the inner end of the rod 5. When the device is to be placed in an inoperative position, the rod 5 is forced inwardly against the tension of spring 30 110 to remove the pin 29 from the groove 28 and the rod is then revolved in the bracket 4 and

sleeve 26 through a half revolution. The pin 29 again enters the grooves 28 to retain the parts in inoperative position. While the offset portion of spring 16 tends to force the colter blade to revolve toward the wheel, the movement of the coulter blade is limited by the engagement of the set screw 7 with the end of the slot 8 and the blade is retained spaced from the wheel.

10 It is to be understood that the form of my invention herewith shown and described is to be taken as a preferred example of the same and that various changes in the shape, size, and arrangement of parts may be resorted to without departing from the spirit of the invention or the scope of the subjoined claims.

Having thus described my invention, I claim:

- 20 1. In a wheeled colter, a supporting bracket having an opening, a rod extending through said opening, a swivel joint mounted on the colter frame, a sleeve arranged in said joint, the inner end of said rod being rotatably mounted in said sleeve, said sleeve being provided with a groove in one end, a blade arranged on the outer end of said rod, a spring engaging said rod and said blade to normally retain said blade in engagement with the side of the colter wheel, and a pin arranged adjacent the inner end of said rod and received in said groove, whereby said blade may be moved to an inoperative position.
- 25 30 35 2. An attachment for wheeled colters comprising a rod arranged adjacent the colter wheel and bent in a substantially hori-

zontal plane whereby its outer end inclines inwardly toward the colter wheel, means for rotatably supporting the inner end of said rod, a blade mounted on the outer end of said rod and adapted to turn independently and coaxially thereof, a spring engaging said blade to normally maintain it in engagement with the colter wheel, means for limiting the movement of said blade toward the colter wheel, and means for holding said rod against rotation.

3. An attachment for wheeled colters comprising a rod arranged adjacent the colter wheel and bent substantially centrally in a horizontal plane whereby its outer end inclines inwardly toward the colter wheel, a supporting bracket having an opening surrounding said rod adjacent the bend therein, a blade mounted on the outer end of said rod and adapted to turn independently thereof, a spring engaging said blade to maintain it in engagement with the colter wheel, means for limiting the movement of said blade toward the colter wheel, a swivel joint mounted on the colter frame, said joint including a sleeve having a slot in one end thereof, the inner end of said rod being mounted in said sleeve, and a pin carried by said rod and normally engaging within said slot.

In testimony whereof, I affix my signature in presence of two witnesses.

THOMAS A. HAMILTON.
